UNITED STATES PATENT OFFICE.

THOMAS H. COSTELLO, OF ENGLEWOOD, ILLINOIS.

HINGE.

SPECIFICATION forming part of Letters Patent No. 328,563, dated October 20, 1885.

Application filed June 16, 1885. Serial No. 168,907. (No model.)

To all whom it may concern:

Be it known that I, THOMAS H. COSTELLO, residing at Englewood, in the county of Cook and State of Illinois, and a citizen of the 5 United States, have invented a new and useful Improvement in Hinges, of which the following is a full description, reference being had to the accompanying drawings, in which—

Figure 1 is an elevation showing two hinges attached to two pieces. Fig. 2 is an elevation showing one hinge attached to two pieces. Fig. 3 is a section at line *x* of Fig. 2. Fig. 4 is an elevation showing one leaf of the hinge with the two connecting wires. Fig. 5 is a 10 section at line *x* of Fig. 4, looking up. Fig. 6 is a bottom view of Fig. 4. Fig. 7 is a section at line *y* of Fig. 4. Fig. 8 is a central vertical section at line *x* of Fig. 6. Fig. 9 is an edge view showing one-half of the hinge. Fig. 10 is a section at line *x* of Fig. 9. Fig. 11 is an elevation showing a single hinge applied to the edges of two pieces. Fig. 12 represents a modification to be used in heavy 15 hinges, similar to those shown in the preceding figures. Fig. 13 is a plan showing a modification containing the leading feature of my invention, and Fig. 14 is an edge view of the modification shown in Fig. 13. Figs. 2 to 14, 20 inclusive, are enlarged as compared with Fig. 1.

The leading object of my invention is to provide a hinge well adapted to be applied to doors, screens, or other articles designed to swing or fold both ways, and which can be 25 cheaply made; and it consists in connecting the two parts or leaves of the hinge by means of two rods or bars, each pivoted at one end to one leaf or part of the hinge and at the other end to the other leaf or part, the rods or bars 30 arranged to cross each other, as shown and described. That which I claim to be new will be pointed out in the claims.

In the drawings, A B represent two pieces of wood, one of which may be considered as a 35 part of the door and the other a strip secured to the casing to receive the door; or these two pieces A B may be considered as two adjoining parts of a screen or other hinged article connected by my hinges.

40 The hinge, as shown in all of the figures except 13 and 14, consists of two parts, C D, connected together by two rods or wires, *a b*.

The edges of the pieces to which the hinges are applied are circular or rounding in form, and the parts C D are adapted to be let into such rounded edges, and are secured thereto by means of screws. (See Fig. 10.) The form of the parts C D will be understood from the drawings, and they are duplicates of each other. The central part of each part C D is provided with a rearward projection, *d*, which is to be let into the strip to which the hinge is applied, and this part D forms a chamber, *g*, to receive the connecting-wires *a b*. These connecting-wires are bent at their ends, and such bent ends are inserted in holes in the upper and lower walls of the chamber *g*, and cross each other diagonally when the parts are in the position shown in Fig. 3, in which the position of one of these wires is indicated by dotted lines. These wires might be loosely riveted in place; but I prefer to hold them in place by means of a metal leaf, *e*, which is provided with two lugs, *f*, which pass through holes in the rear wall of the chamber *g*, and are riveted thereto, as shown in Fig. 7. These leaves *e* are located between the two connecting-wires or rods *a b*, and prevent them from slipping out of place, the leaves *e* being inserted and riveted in place after the wires *a b* have been inserted in their receiving-holes.

In Figs 2 and 3, the two parts A B are in the same plane, and in Fig. 11 the two parts A B are parallel to each other.

In use, if the hinge be attached to two movable parts either one can be swung over and around the other, the ends of the wires *a b* being the pivotal points, and the position of these wires changing relative to each other, as indicated in the drawings. The connecting-wires *a b* are of the same length, *a* being connected at one end to C, a little to the right of its center, and the other end being connected to the right of the center of D, while the wire *b* is connected to the left of the center of C and to the left of the center of D, looking at Fig. 11; or, to state this in another way, the opposite ends of the wires are connected to opposite sides of the parts C D, as shown in Fig. 3, and these wires being of the same length, and being connected as described, allow the rotating part to swing in a circle. Suppose the piece A to be fixed. Then the piece B can be made to swing from one side

to the other of A. If neither part A nor B is fixed, but they are only hinged to each other, either one can swing upon the other, and the two parts can be folded together, as shown in Fig. 11, and they may be folded together either way.

If the hinges are to be used with heavy articles, it may be desirable to provide them with an additional support, which may be done as shown in Fig. 12, in which the part D is provided with a recess, h, near its lower end, and the part C is provided with a projection, i, which enters the said recess. As the hinges swing the projection i moves in the recess h, and thus a bearing is formed which aids to prevent the sagging of the parts.

In Figs. 13 and 14 I have shown a hinge containing the leading feature of my invention, but adapted to be let into and secured to the ends of two pieces, A B. In these figures (13 and 14) C' D' are two flat parts or leaves. a' is a bar having its opposite ends pivoted to opposite sides of the two leaves, and b' is another similar bar having its opposite ends pivoted to opposite sides of these leaves, as indicated by dotted lines in Fig. 13. These bars a' b' take the place of the rods a b, before described. One part of this hinge shown in these figures (13 and 14) can be swung around the other so that when used the effect is the same as when the form shown in the preceding figures is used. The hinge shown in Figs. 13 and 14 is also adapted to be secured to the sides of two pieces which are designed to be folded over onto each other lengthwise. It will be observed by looking at Fig. 13 that if the leaf

C' remains stationary the other leaf, D', can be folded over so that its upper edge will rest upon the upper edge of C'.

What I claim as new, and desire to secure 40 by Letters Patent, is—

1. A hinge consisting of the leaves C and D, having circular adjacent edges and rigid bars a and b, pivotally connected at their ends to the leaves, respectively, and arranged diagonally to each other at opposite sides of the leaves, substantially as shown and described. 45

2. A hinge consisting of two leaves or parts, C D, each having a chamber, g, in combination with two rods or bars, a b, pivoted to the parts C D, substantially as and for the purposes specified.

3. A hinge consisting of two leaves or parts, C D, each having a chamber, g, in combination with two rods or bars, a b, pivoted to the parts C D, and pieces e, secured in the chamber g and between the rods or bars a b, substantially as and for the purposes specified.

4. The combination, in a hinge, of the parts or leaves C D, rounded or circular at their meeting edges, as shown, and connected together by bars a b, pivoted at their opposite ends to opposite sides of the two leaves, the rounded or circular portion of part D being provided with recess h and the rounded portion of part C provided with the projection or flange i, which fits and has its bearing in the recess h, substantially as described. 65

THOMAS H. COSTELLO.
